DRESS

Barbara C. Tilhou, Philadelphia, Pa., assignor to Rosenau Brothers, Inc., a corporation of Pennsylvania

Application June 5, 1953, Serial No. 25,339

Term of patent 3½ years

(Cl. D3—26)

To all whom it may concern:

Be it known that I, Barbara C. Tilhou, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof.

In the drawing:

Fig. 1 is a front view of a dress, showing my new design.

Fig. 2 is a rear view of the dress shown in Fig. 1.

Fig. 3 is a side view of the dress as shown in Figs. 1 and 2.

Fig. 4 is an enlarged view of a fragmentary section of the dress.

I claim:

The ornamental design for a dress, substantially as shown.

BARBARA C. TILHOU.
